UNITED STATES PATENT OFFICE.

IRA D. SHARP, OF NICHOLASVILLE, KENTUCKY.

APPARATUS FOR PRINTING PHOTOGRAPHIC PRINTS FROM NEGATIVES.

Application filed September 9, 1922. Serial No. 587,098.

To all whom it may concern:

Be it known that I, IRA D. SHARP, a citizen of the United States, and a resident of Nicholasville, in the county of Jessamine and State of Kentucky, have invented certain new and useful Improvements in Apparatus for Printing Photographic Prints from Negatives, of which the following is a specification.

10 This invention relates to an apparatus for the printing of photographic prints from negatives.

An object of the invention is the provision of a device for printing photographs in which the intensity of the light may be varied as the density of the negatives and in which the time of exposure remains constant for photographic papers of constant speed.

20 A further object of the invention is to provide a device for printing photographs having an automatically controlled time element for operating a switch of an electric lighting circuit to close the circuit whereby 25 the proper exposure may be had. Means are also employed in connection with the time element for varying the time of exposure according to the sensitiveness of the paper.

In the accompanying drawings forming a 30 part of this application and in which like reference numerals are employed to designate like parts throughout the same,

Figure 1 is a view in perspective of the apparatus for the printing of photographic prints from negatives.

Figure 2 is a longitudinal vertical section of the same.

Figure 3 is a transverse horizontal section taken on the line 3—3 of Figure 2.

40 Figure 4 is a diagrammatic representation of the wiring.

Referring to the drawings, 1 designates a table having pairs of standards or legs adapted to support the top of the table in an elevated position above the floor of the room and at a height above said floor which is most convenient for manipulating certain parts of the apparatus.

At the one end and in the top of the table 50 is formed a rectangular opening 2 below which and to the under face of the table is secured a cabinet 3 in the shape of a parallelopiped. A transparent member 4, preferably in the form of a sheet of glass is

mounted over the opening 2 and in a counter-sunk groove formed adjacent the periphery of the opening 2 whereby the top of the glass 4 will be flush with the upper surface of the table 1, the glass 4 forming a support for the photographic paper 5 and the negative 6.

The end walls of the cabinet 3 are slotted as shown at 7 in Figure 1, the slots being adapted to receive a ground glass 8.

Upon the floor 9 of the cabinet are secured sockets 10, 11, 12 and 13 which are 65 adapted to respectively receive and support light bulbs, 14, 15, 16 and 17.

Secured to the bottom of the cabinet 3 are a pair of spaced brackets 18 having insulating members 19 adapted to support a conductor 20 in the shape of a hollow rod. To the socket 10 is secured a switch 21 formed of resilient metal, such as brass and having a spring member 22 secured to the under face of the switch 21 with the outer ends of the switch and springs spaced from each other and located above the conductor 20. To the sockets 12 and 13 are respectively secured switches 23 and 24 having a spring member 22 secured to the switch with the free end of the spring and switches spaced above the conductor 20. Similarly disposed operating rods 25, 26 and 27 are vertically mounted at one side of the cabinet 3 and are adapted to respectively operate the switches 21, 23 and 24.

The insulating members 19 are held in position between the brackets 18 and a bar 28 with the last mentioned bar provided with a plurality of perforations which are adapted to receive the lower ends of the operating rods 25, 26 and 27. The upper ends of the said operating rods project through openings 29 in the top of the table 1. Each rod is provided with a shoulder 30 and thereby forming a reduced hand grip 31, with the shoulder 30 being adapted to engage the under face of the table 1 adjacent the passage 29 and lock the rod in its lowermost position for maintaining the switch 21 and spring 22 in engagement with the conductor 20.

To a block 32 secured transversely of the table top are hingedly connected the arms 33 which carry a platen 34. The length of the arms 33 and the position of the pivotal connection of the arms with the block 32 is such as to permit the platen when moved to

its lowermost position to cover the transparent plate 4 over the opening 2 and maintain the photographic paper 5 and negative 6 in firm engagement with the transparent plate 4. A bracket arm 35 projects outwardly from the lower end of one of the supporting arms 33. To the free end of this arm 35 is connected one end of a spring 36 with the other end of the spring secured 10 to an eye bolt 37 adjustably mounted in a bracket 38. The spring 36 tends to maintain the platen 34 in its most elevated position above the transparent member 4 and out of engagement with the same.

15 Adjacent an opening 39 in the table top is secured a plate 40 having an opening 41 in alignment with the opening or passage 39. The walls of the openings are tapered with the area of the opening being greatest where 20 said opening is formed through the under face of the table 1.

25 A pendulum 42 having a pivot pin 43 is mounted in bearings formed in the plate 40 whereby the pendulum is free to oscillate in the aligned openings 39 and 41.

30 A curved bracket arm 44 depending from the supporting arm 33 of the platen 34 projects through an opening 45 in the top of the table with the free end of the said arm connected to a spring 46. A flexible member 47 connects the other end of the spring to the lower section of the pendulum 42.

35 A bumper 48 secured to the rear side wall of the cabinet 3 projects laterally outwardly toward the pendulum 42 and is adapted to engage said pendulum and maintain the same in a position, inclined to the vertical as shown in Figure 2 and when the platen 34 is maintained in its most elevated position by the springs 36. The resilient member 46 and the flexible member 47 connecting the pendulum 42 with the arm 44 which latter is connected with the platen 34, form a connection between the pendulum and the platen for retaining the pendulum in engagement with the bumper 48 when the platen is elevated as shown in Figure 2.

40 A slidable weight 49 is mounted on the lower end of the pendulum 42 and maintained in any one of a plurality of positions along the lower end of the pendulum by means of a set screw. A second slid- 45 able weight 50 is mounted upon the upper end of the pendulum and above its pivotal point 43 and cooperates with the weight 49 to substantially shorten the pendulum and thereby provide a more rapid oscillation of the pendulum.

46 A resilient contact 51 is mounted on the plate 40 adjacent the pivotal connection of the pendulum 42 and is adapted to engage a contact 52 movable relative to the contact 51 and mounted on the pendulum 42 adjacent the upper free end of the contact 51. The members 51 and 52 are adapted

to have contact after release of the pendulum 42 and about the time that the pendulum is located in a vertical. While I have shown these contacts adapted to engage when the pendulum is located in the vertical, the said contacts may be caused to engage at any other position of said pendulum. The resilient contact 51 permits the pendulum to continue its oscillation beyond the vertical. 70

75 A pair of wires 53 and 54 are connected with a plug adapted to be screwed into a wall socket connected with a source of current. The two wires for convenience are located in the same conduit and insulated 80 from each other. The wire 53 leading in through an opening in the cabinet 3 is connected with the binding post of the red light 17 which is normally in circuit to give a red light at all times when the printing device is in operation. The wire 54 is connected to the other binding post of the socket 13. The wire 54 is continued to the binding posts on one side of the sockets of the lights 15, 16 and 14. The hollow conductor 90 20 is connected by means of a wire 55 which leads to and is connected to the resilient contact 51 on the table 1. A wire 56 connected with the movable contact 52 returns to the cabinet 3 and is connected with the leading 95 in wire 53 at the binding post 57 of the red light socket.

100 Referring to Figure 4, the wiring dia- 105 gram is shown in which the lead-in wire 53 is carried to the binding post of the red light 17 and thence to the movable contact switch 52 through the current passing through the contact 51 through the wire 56 to the conductor 20 and thence through the switches 21, 23 and 24 through the respective lamps 14, 16 and 15 and then through the wire 54 to the plug.

110 The lamp 14 is of a certain candle power which is sufficient to print the most transparent negative and is designated as 1 light unit; the lamp 16 is of sufficient candle power when compared to lamp 14 to give $1\frac{1}{2}$ light units; the lamp 15 as compared to lamp 14 will give 2 light units. By this arrangement and the relation between the 115 different lamps many different combinations of light units may be had depending upon the density of the negative to be printed. If it be desired to have $2\frac{1}{2}$ light units for certain negatives rods 25 and 26 will be depressed thereby placing lamps 14 and 16 in circuit and giving $2\frac{1}{2}$ light units, or lamps 15 and 16 may be thrown in the same circuit by operating rods 26 and 27, thereby giving 120 $3\frac{1}{2}$ light units; or lamps 14 and 15 may be placed in circuit by operating rods 25 and 27, thereby giving 3 light units or all three rods may be depressed thereby giving $4\frac{1}{2}$ light units. If it be desired to increase the 125 number of light units a lamp will be added 130

to the cabinet 3 and placed in circuit with a corresponding operating rod and switch, the light units of which will be slightly greater than all of the light units combined which are now shown in the said cabinet such as for instance a lamp that will give at least five light units. This additional lamp can be combined with other lamps to form new combinations of light units.

10 In the use of the ordinary incandescent lamp it will be observed that the spot directly above the incandescent filament of the lamp will give the greatest intensity of light and therefore I cover the top of the globe 15 by means of some semi-transparent material as shown at 58 for preventing this intense light from effecting one particular spot on the printing paper which is directly over the filament.

20 The operation of my device is as follows: The plug connected to the wires 53 and 54 is inserted in the usual socket in the wall of a room whereby the lamp 17 which has a red globe is illuminated thereby giving sufficient light for operating the device without effecting the printing paper. The negative 6 is placed on the transparent covering 4 over the opening in the top of the cabinet 3 with the printing paper 5 placed on the top 25 of said negative with the sensitive portion of the paper facing the opening in the cabinet. The negative is supported by the transparent covering 4. After the operator has inspected the negative and determined what lamp, say 14, is necessary for properly printing the paper, the rod 25 is moved downwardly forcing the switch 21 into contact with the conductor 20.

30 The platen 34 is moved rapidly downward upon the paper 5 for maintaining the paper in close association with the felt member 60 and in engagement with the negative 6. When the platen is moved upon the paper 5 the arm 44 connected with said platen is moved rapidly through the opening 45 in the top of the table and releases the tension of the spring 46 and thereby permitting the pendulum 42 to freely oscillate. As shown in Figure 2, when the pendulum is moved to a vertical position the contact members 51 and 52 will make instant contact and cause the circuit to pass through the wires 55 and 56, conductor 20, switch 21, and illuminating lamp 14. The instant that the pendulum 42 passes the line 61 indicating the vertical position of the pendulum on its return stroke, the current will be broken and lamp 14 will be extinguished.

35 If it be desired to use more than one lamp such as 14 and 16, both rods 25 and 26 will be moved downwardly and lock the switches 21 into engagement with the conductor 20 so that when the platen 34 is again operated 40 to its lowermost position the pendulum 42

will be released and again provide contacts between the members 51 and 52 for an instant closing of the circuit and for illuminating lamps 14 and 16. The spring 36 always returns the platen 34 to its most elevated position with the pendulum 42 in engagement with the bumper 48 and the contacts 51 and 52 out of engagement.

45 It will be noted that when the pendulum 42 is released and reaches the vertical line 61 the contacts 51 and 52 will engage each other and remain in engagement until the pendulum on its return stroke passes the vertical line 61. When the platen 34 is released the pendulum 42 will be maintained 50 in the inclined position shown in Figure 2. If it be desired to provide for shorter time exposures the slidable weight 49 is moved near to the pivot 43 of the pendulum as it is desired to limit the engagement between 55 the contacts 51 and 52 when the pendulum is oscillating beyond the vertical line 61. The adjustment of the weights 49 and 50 either increases or decreases the time of vibration of the pendulum and therefore the time of contact between the members 51 and 52 and therefore the exposure of the light within the cabinet 3. When necessary all three lights or any combination of lights may be employed for exposing the prints.

55 When any of the rods 25, 26 or 27 are depressed the switch 21 being made of spring material is forced downwardly with the spring member 22 moving in advance of the switch and engaging the conductor 20. When the shoulder 30 of said rods is engaged with the under face of the table 1 the spring 22 and the switch 21 will be locked in face to face engagement and on the conductor 20. When the shoulder 30 is released 60 from the periphery of the passage 29 of the table the switch 21 will be first to move upwardly while the spring 22 will be somewhat delayed in its progress before being elevated out of contact with the conductor 20 and therefore the rods 25, 26 and 27 will not be forced rapidly out of their passages within the aligned passages through which the rods operate in the table 1 and the bar 28. The upward movement of the 65 switch 21 is therefore restrained through the co-operation of the spring 22. The spring also compensates for wear.

70 What I claim is:

75 1. A printing machine comprising a cabinet having a printing opening in the top and a sheet of glass supported over the opening, a ground glass spaced from the opening and supported in the cabinet, an electrically controlled illuminating device in the cabinet below the ground glass for supplying a white light, a circuit connected with the illuminating device, means connected with the circuit for varying the intensity of the light supplied, a platen pivotally 80

- mounted on the cabinet and movable into engagement with the sheet of glass over the opening in the cabinet, a resilient means for maintaining the platen suspended above the glass, a pendulum mounted for oscillation on the cabinet and resiliently connected with the platen whereby said pendulum is held to one side of the vertical when the platen is suspended above and out of engagement with the sheet of glass, a switch on the pendulum connected with a lighting circuit adapted to temporarily close the lighting circuit when the platen is moved into engagement with the sheet of glass and the pendulum is oscillated, said circuit being adapted to be maintained open by the pendulum when said platen is in normal inoperative position.
2. In a printing machine for the printing of photographic prints, a cabinet provided with an opening, a transparent cover for the opening, an illuminating device in the cabinet below said opening, an electric circuit controlling the lighting device, a platen pivotally mounted on the cabinet, means for maintaining the platen elevated above the opening but permitting said platen to be moved into engagement with the transparent covering, an arm depending from the platen, a pendulum mounted for oscillation on the cabinet, a resilient means connecting the pendulum with the depending arm, whereby when the platen is elevated the pendulum is maintained at one side of the vertical and when lowered said pendulum is released for oscillation, an electric contact on the pendulum forming one end of the lighting circuit, and a resilient contact on the cabinet forming the other end of said circuit, said contact on the pendulum engaging the resilient contact when the pendulum is oscillated, said circuit being adapted to be maintained open by the pendulum when said platen is in normal inoperative position.
3. In a printing machine for the printing of photographic prints, a cabinet provided with an opening, means for supporting a negative and a photographic paper over the opening, an illuminating device below said opening, an electric circuit controlling the lighting device, a platen pivotally mounted on the cabinet, a time element oscillatable on the cabinet and connected with the electric circuit for closing said circuit during a portion of the time of the oscillation of the time element, and a connection between the time element and the platen for maintaining the time element in inoperative position, and the circuit open, said connection releasing the time element when the platen is moved onto the opening in the cabinet.
4. In a printing machine for the printing of photographic prints, a cabinet provided with an opening, means for supporting a negative and a photographic paper over the opening, an illuminating device below said opening, an electric circuit controlling the lighting device, a platen pivotally mounted on the cabinet, a time element oscillatable on the cabinet and connected with the electric circuit for closing said circuit during a portion of the time of the oscillation of the time element, and a connection between the time element and the platen for maintaining the time element in inoperative position, and the circuit open, said connection releasing the time element when the platen is moved onto the opening in the cabinet.
5. In a printing machine, a cabinet having a printing opening in the top, a transparent means supported over the opening, an electrically controlled illuminating device in the cabinet below the opening for supplying the white light, a circuit connected with the illuminating device, means for varying the degree of illumination, a platen pivotally mounted on the cabinet and resiliently maintained in elevated position and adapted to be moved into engagement with the transparent means on the opening in the cabinet, a pendulum mounted for oscillation on the cabinet, a resilient means connecting the pendulum with the platen whereby oscillation of the platen releases the pendulum for oscillation, and means on the pendulum for opening and closing the circuit of the illuminating device, the pendulum being adapted to maintain the circuit normally open when the platen is in an inoperative position.
6. In a printing machine, a cabinet having a printing opening in the top, a transparent means supported over the opening, an electrically controlled illuminating device in the cabinet below the opening for supplying the white light, a circuit connected with the illuminating device, means for varying the degree of illumination, a platen pivotally mounted on the cabinet and resiliently maintained in elevated position and adapted to be moved into engagement with the transparent means on the opening in the cabinet, a pendulum mounted for oscillation on the cabinet, a resilient means connecting the pendulum with the platen whereby oscillation of the platen releases the pendulum for oscillation, means on the pendulum for opening and closing the circuit of the illuminating device, and means connected with the pendulum for varying the time of illumination in the cabinet, the pendulum being adapted to maintain the circuit normally open when the platen is in an inoperative position.
7. In a printing machine comprising a cabinet having a printing opening in the top, a sheet of glass supported over said opening, an electrically controlled illuminating device in the cabinet, a circuit connected with the illuminating device, a platen

mounted for oscillation on the cabinet and adapted to be projected into engagement with the glass on the opening in the cabinet, a pendulum mounted for oscillation on the cabinet, a resilient contact on the cabinet, a second contact on the pendulum, means connecting the platen with the pendulum for maintaining the pendulum at an angle to the vertical, said means permitting oscillation of the pendulum when the platen is depressed whereby the contact on the pendulum will engage the fixed contact on the cabinet, said contacts being in circuit with the circuit connected with the illuminating device, the pendulum being adapted to maintain the circuit normally open when the platen is in an inoperative position.

8. In a printing machine comprising a cabinet having a printing opening in the top, a sheet of glass supported over said opening, an electrically controlled illuminating device in the cabinet, a circuit connected with the illuminating device, a platen mounted for oscillation on the cabinet and adapted to be projected into engagement with the glass on the opening in the cabinet, a pendulum mounted for oscillation on the cabinet, a contact on the cabinet, a second contact on the pendulum, means connecting the platen with the pendulum for maintaining the pendulum at an angle to the vertical, said means permitting oscillation of the pendulum when the platen is depressed whereby the contact on the pendulum will engage the fixed contact on the cabinet, said contacts being in circuit with the circuit connected with the illuminating device, and means for varying the time of oscillation of the pendulum, the pendulum through the platen being adapted to maintain the contacts out of engagement when the platen is in an inoperative position.

9. In a printing machine comprising a cabinet having a printing opening in the top, a sheet of glass supported over said opening, an electrically controlled illuminating device in the cabinet, a circuit connected with the illuminating device, a platen mounted for oscillation on the cabinet and adapted to be projected into engagement with the glass on the opening in the cabinet, a pendulum mounted for oscillation on the cabinet, a contact on the cabinet, a second contact on the pendulum, means connecting the platen with the pendulum for maintaining the pendulum at an angle to the vertical and the contact on the pendulum out of engagement with the contact on the cabinet to maintain the circuit open, said means permitting oscillation of the pendulum when the platen is depressed whereby the contact on the pendulum will engage the fixed contact on the cabinet, said contacts being in circuit with the circuit connected with the illuminating device.

10. In a printing machine comprising a cabinet having a printing opening in the top, a transparent member supported over the opening, an illuminating device in the cabinet comprising a plurality of lamps, an electric circuit connected in series with the lamps, switches connected with the lamps and projecting through the cabinet, a conductor connected with the circuit and spaced below the switches, operating rods engaging the switches for depressing the switches into contact with the conductor, and means for locking the operating rods in depressed position for maintaining the switches in contact with the conductor.

11. In a printing machine for the printing of photographic prints, an illuminating device, means for supporting a negative and photographic printing paper in face to face engagement and within effective relation with the illuminating device, means for regulating the intensity of the light in accordance with the density of the negative, and means for automatically effecting illumination of the illuminating device, for definite periods of time and independently of the duration of the time the negative is supported on the supporting medium.

12. In a printing machine for the printing of photographic prints, an illuminating device, means for supporting a negative and photographic printing paper within effective light exposed relation with the illuminating device, means for regulating the intensity of the light from the illuminating device in accordance with the density of the negative, means regulating the time of exposure in accordance with the speed of the photographic printing paper, and means automatically operating the electric illuminating device, for definite periods of time and independently of the duration of the time the negative is supported on the supporting medium.

13. In a printing machine for the printing of photographic prints, an illuminating device, means for supporting a negative and photographic printing paper within effective light exposed relation with the illuminating device, means for regulating the intensity of the light from the illuminating device in accordance with the density of the negative, said illuminating means comprising an electric circuit, a plurality of lamps adapted to be connected with said circuit, one of said lamps being comprehended as a unit of light with the other lights progressively advanced in intensities to form multiples of the unit lights, and switches in the circuit for controlling the introduction of any or all of the lamps into the circuit.

14. In a printing machine for the printing of photographic prints, an illuminating device, a plurality of lamps adapted to be connected with said circuit, an electric con-

conductor in the circuit and spaced from the lamps, switches connected with the lamps and spaced above the conductor, a spring connected with each switch and operated in advance of the switches for engaging the conductor, operating rods for each switch adapted to force the spring and switch into engagement with the conductor, and means for locking the rods in position when the switches have been closed, said springs adapted to return the rods to an inoperative position.

IRA D. SHARP.
